UNITED STATES PATENT OFFICE.

LAWRENCE KLINKER, OF SAN FRANCISCO, CALIFORNIA.

BASEBALL GAME.

Application filed February 23, 1921. Serial No. 447,102.

To all whom it may concern:

Be it known that I, LAWRENCE KLINKER, a citizen of the United States, residing at the city and county of San Francisco and 5 State of California, have invented new and useful Improvements in Baseball Games, of which the following is a specification.

This invention relates to a game apparatus, and especially to a game board designed 10 for playing the game of base ball.

One of the objects of the present invention is to provide a game board adapted for the playing of base ball, and particularly to provide a game of this character which is 15 not altogether a game of chance, but one requiring both thought and skill, and which will afford considerable amusement to the players.

Another object of the invention is to provide a game board which will permit the game of base ball to be simulated with considerable accuracy, and wherein the player, by the rolling of a ball, may make bases, homeruns, strikes, balls, fouls etc., and in 20 fact any of the plays of a regular game.

Another object of the invention is to provide a game of the character described which may be played by two players, and which permits one player to counteract or defeat 25 the plays made by the other player.

Further objects will hereinafter appear.

The invention consists of the parts and the construction, combination and arrangement of parts as hereinafter more fully described and claimed, having reference to the 35 accompanying drawings, in which

Fig. 1 is a plan view of the game board.

Fig. 2 is another plan view showing the upper board removed and disclosing a part 40 of the interior mechanism.

Fig. 3 is another plan view showing the two intermediate oppositely inclined runways removed.

Fig. 4 is a side elevation in section taken 45 on line 4—4, Fig. 2.

Fig. 5 is a cross section on line 5—5, Fig. 4.

Fig. 6 is a front end view of Fig. 1.

The apparatus by which the present game is played consists of a box-like structure 50 embodying side sections 2, end sections 3, a front receiving pocket 4, and an inclined bottom section 5. Forming a cover for the box-like structure is a game board 6, and formed in said board is a plurality of openings, three at one end of the table marked 55 1st, 2nd and 3rd, and four openings in the

opposite end of the table which are marked "home-run 1, 2 and 3." Formed at the end of the board 6, beyond the home run opening, is a series of pockets generally indicated at 7, said pockets being provided for the reception of balls which are not intercepted by the openings just specified, and which when played represent such plays as fouls, balls and strikes. Disposed interior of the box-like structure, intermediate the bottom section 5 and the top board 6, is a pair of oppositely inclined runways 8 and 9. The runway 8 receives a ball hereinafter to be known as the "putout ball", 70 and which is inserted through any one of the openings marked 1st, 2nd and 3rd. The oppositely inclined runway 9 conversely receives any ball which is intercepted by the openings marked "home-run 1, 2 and 3," 75 and this runway also receives the balls which are intercepted or caught in the pockets 7 as will hereinafter be described.

In playing the game there are two players one representing each team, and these 80 players will of course alternately play against each other, one representing the team at bat, and the other the field team. These players stand in front of the main pocket indicated at 4. The player at bat 85 is provided with a suitable number of small balls, while the field player is provided with one single "putout" ball, which is preferably larger and heavier than the small balls employed by the player at bat. The 90 player at bat starts playing by rolling one of the small balls from the point indicated at 10. He rolls the ball in the direction of arrow a, and if he is skilled and at the same time lucky, it is possible that the ball 95 may be intercepted by one of the openings marked 1st, 2nd and 3rd, or the home-run opening; considerable skill being required to enter the home-run opening as this is disposed intermediate the openings 2 and 3, 100 and, practically speaking, directly behind the opening 1. In other words, it is, practically speaking, necessary to impart a spinning movement which will cause the ball to slightly curve when rolling to make it 105 possible to enter this opening. If a poor play or roll is made, it is obvious that the ball will miss the first four openings mentioned, and it will in that instance enter one of the pockets indicated at 7.

Assuming that the first ball rolled by the player at bat falls into the opening marked

1. If this should happen it is obvious that the ball will drop through the opening and fall on the inclined runway 9 disposed directly below the same. A ball dropping 5 through the opening marked 1, strikes the runway 9 at the point indicated at 11. A ball dropping through the opening marked 2, strikes at the point indicated at 12. A ball dropping through the opening marked 10 3, strikes at the point indicated at 13, while a ball dropping through the home-run opening strikes at the point indicated at 14. Any ball striking the inclined table, at the points indicated at 11, 12 and 13, will enter a 15 tortuous passage, generally indicated at 15, and will run down this passage in the direction of arrow *b*, and it will, unless the opposing or field player is quick in action, drop through an opening indicated at 16. 20 This opening deposits the ball on the lower end of the inclined runway 8, from where it runs down the incline in the direction of arrow *c*; being guided during its downward travel by guide plates 17 which direct the 25 ball to a stop pin 18 and a movable guide flange 19. The only method of defeating this play, or preventing the ball from dropping through the opening 16, is for the field player to drop his putout ball through the 30 opening marked 1st, that is he drops the ball through this opening if the ball played by the man at bat happens to drop through the opening marked 1, which represents first base. If the field player is quick and 35 drops the putout ball through the opening marked 1st, it is obvious that this ball will strike the upper end of the inclined runway 8 and will roll down said runway along a guide plate 20; the ball finally leaving 40 the runway and dropping into a chute 21, which is pivotally supported on the bottom section 5 as indicated at 22.

Now if the putout ball reaches the chute 21, before the ball played by the man at 45 bat reaches the opening 16, it is obvious that the field player's ball will depress the chute 21. If this happens a bridging plate carried by the chute 21, and indicated at 23, will move into alignment with the opening 50 16 and form a runway thereacross. The man's at bat ball will then roll across the bridging plate and finally drop through an opening 24, where it will reach the inclined bottom section 5 and pass downwardly 55 through a discharge runway leading into a pocket indicated at 4^a. This pocket represents "outs" as shown in Fig. 6 and shows that the field player struck out the man at the bat. Now suppose that the man at the 60 bat rolls another ball and that it drops into the second base opening indicated by the numeral 2. Further suppose that the field player is a little slow in placing the putout ball in the opening marked 2nd, in that 65 case the putout ball will be too slow to reach

the depressible chute 21 and the ball rolled by the man at bat will then have a chance to pass through the opening 16 and reach the stop members 18 and 19 where it is temporarily arrested. This means that the man 70 at bat has reached second base.

Now suppose that a third ball is rolled and that it drops through the home-run opening. In that instance it will strike the inclined runway 9 at the point indicated 75 at 14, from where it will roll down the side of the runway 9 and drop into a short chute 25 carried by a pivotally mounted lever 26. On striking this chute it will depress the lever 26 and raise the guide plate 19 supported thereby. The ball which reached second base, and which was temporarily held at this place, will be released and the home-run ball is also released; both balls striking the bottom section 5 where they 80 will roll down the inclined portion of the same or a runway formed thereon which leads into a pocket marked 4^b and indicated by the word "runs," see Fig. 6. Two balls will in that instance be deposited in the 90 "runs" pocket, showing that the man at bat has made two runs. There is no way of putting out the man at bat if he makes a home-run, nor is there any way of intercepting any balls, whether one or more, 95 which may be resting on bases as these are released when the guide plate 19 is raised, and will be deposited in the same runway which leads to the runs pocket, that is the balls released by a home-run play will all 100 run down the common runway, generally indicated by the arrow *d*, and will deposit in the pocket 4^b. The putout ball, which is the only ball used by the field player, will always roll into the chute 21 and will from 105 this chute roll into the pocket indicated at 4^c, so that it is returned to the field player who must use it over and over again for each play. "Outs" will land in the pocket marked 4^a and the balls entering the foul, 110 ball, and strike pockets will enter the pocket at 4^d, that is any balls which happen to enter the foul, ball or strike pockets are automatically released and returned to the pocket 4^d by the putout ball whether it is dropped 115 through the 1st, 2nd or 3rd opening. When dropped through any of these openings, it lands on the inclined runway 8 and will not pass off this runway before striking the end of a pivotally mounted lever 30. This lever is connected with a string 31, or similar connection, the opposite end of which is attached to a rocking bottom member 32. This rocking bottom member is disposed below the foul, ball and strike pockets, and any balls deposited in said pockets are thus automatically released every time the putout ball is played, as it always trips this lever before it is returned to the player. 120

During one inning it is possible that the 130

man at bat may make one, two or three bases. Such balls will be retained by the stop pin 18 and the movable guide plate 19 and will be held in this position until the 5 end of the inning, unless a home-run play is made. Now it is possible that the man at bat may not make a home-run, and if this is the case it is obvious that means must be provided for releasing the balls on base 10 when the inning is over. This is accomplished by employing a bell crank lever. This lever is provided with a handle 40 which projects through a slot 41 formed in the top board 5, and as previously stated is 15 only employed for the purpose of releasing any balls which will be retained by the plate 19 and the stop member 18 when the end of an inning has been reached. When it is desired to release these balls, it is only necessary to grasp the upper end of the handle, 20 and to rock it in the direction of the arrow, see Fig. 1. This causes the end of the lever indicated at 42 to engage the lever 26, and thereby impart a rocking movement to the same, which will raise the plate 19 and release the balls retained thereby. These balls will of course enter the runway *e*, as they are led into the same by a guide 74, and will 25 finally deposit in the pocket 4^a.

To render it comparatively easy to maintain the score and visibly indicate the same, I have provided a series of indicators such as shown at 50, 51, and 52. These indicators each cooperate with a graduated or numbered circle such as shown, and by turning the indicators it is possible to score 30 the runs made in each inning and the number of innings played. For instance the field player may use the indicator indicated at 50 to score his runs, the man at bat the indicator shown at 51, and the last indicator shown at 52, may be employed for 35 the purpose of recording the innings. The score or standing of the game is thus visibly indicated at all times, an obvious advantage, and will probably be the source of amusement to "onlookers", etc.

One of the features of the present invention is to eliminate the so called game of 40 chance as much as possible, that is the man at bat will play a better game if a certain amount of skill is employed, similarly the fielder or opposing player will play a better game if he thinks fast and places the 45 putout ball quickly in the particularly opening required. With this object in view the runways connected with the several openings are made in such a manner that the time element involved varies according to 50 the play made. For instance if a home-run is made by the man at bat, the game is so arranged that the home-run cannot be stopped, nor any balls which have reached base, and which will be 55 released thereby. The opposing player, 60 however, has the chance to put out balls reaching first, second or third base through the openings 1, 2 and 3, and particularly a ball entering the third base opening as this has a further distance to travel through 65 the tortuous runway indicated by arrow *b* than the ball which enters the first base opening. See points indicated at 12, 11 and 13, that is a ball entering through the opening 3 has such a distance to travel down the 70 tortuous runway that the time element is slightly greater than when the ball enters through the first base opening; this time element being sufficient to permit the field player to drop his putout ball and reach the 75 depressible chute 21 before the other ball reaches the opening 16. If this happens, the played ball will obviously not reach base and an out will be registered.

To further illustrate the time element involved, reference is made to Fig. 2, wherein the openings marked 1st 2nd and 3rd are indicated. The putout ball is delivered to the runway 8 through said openings. The distance between the opening marked 1st 80 and the discharge point of the runway is the shortest. The distance between the discharge and the opening marked 2nd is a little greater, and the distance between the opening marked 3rd and the discharge point 85 is still greater. This increase of distance varies the time element and to this extent 90 the chance of defeating the play made by the man at bat.

To assist the man at bat to a certain extent, I prefer to slightly curve the end of the board 6, or that portion which registers with the openings marked 1, 2, 3, and home-run, that is the upper surface is slightly concave as shown in Fig. 5, and as such increases the chances of playing the ball in 95 the home-run opening.

The game board here shown may be constructed as small or as large as desired. Certain game boards may possibly be built 100 as large as a billiard table, and others again may be so small that they may be placed on top of an ordinary table. In certain instances, particularly when larger tables are employed, I prefer to visibly indicate 105 the number of balls on base, or in other words the number of balls retained by the stop pin 18 and the plate 19. With this object in view, an electric light is placed adjacent each opening marked 1st, 2nd and 110 3rd. These lights are in circuit with the stop pin 18 and contact points generally indicated at 70, 71 and 72. If one ball reaches base or engages the stop pin 18, a circuit 115 will be formed through the stop pin and the contact 70, and as these are connected through wires with a battery 73 and the electric bulb positioned adjacent the opening marked 1st, it is obvious that this will 120 be lighted and that a visible display will be 125 130

made when one ball reaches base. A similar visible indication will be made if two or more balls reach base as the several contacts 70, 71 and 72 are connected with the respective lights.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or varying uses may demand.

By referring to Fig. 2 of the drawings it will be seen that the guide plate 19 which operates with the stop pin 18 is just sufficiently long to retain three balls which 20 would assume the positions shown at 70, 71 and 72. It is possible that the man at bat when playing may during one inning obtain three bases. If this is the case the three places indicated at 70, 71 and 72 would be 25 filled, and if the man at bat should still make another base it is obvious that there would be no room to retain the same, and it would therefore roll off the table 8 into the runway, D, which would direct it to the runs pocket. 30 The man at bat would in that instance gain a run and might gain one or more runs in this manner.

Having thus described my invention, what I claim and desire to secure by Letters Patent is—

1. A game apparatus comprising a game board, a bottom board, a pair of oppositely and vertically inclined overlapping boards positioned intermediate the game board and 40 the bottom board adapted to receive opposing playing elements, tortuous runways formed on the upper surface of each of the inclined boards, said game board having a plurality of openings therein communicating with said runways, the said playing elements adapted to be manipulated on the game board to pass through said openings on to said runways.

2. A game apparatus comprising a game board having a series of openings formed therein, an inclined bottom board, a pair of inclined boards positioned between said game board and said bottom board, said inclined boards being vertically and oppositely inclined, and having overlapping ends, tortuous runways formed on the upper surface of said inclined boards, and playing elements which may be manipulated on the game board to pass through the openings 55 therein on to the runways in opposition to each other by which their path of travel is controlled.

3. A game apparatus comprising a game board having a plurality of openings formed 60 therein representing different plays of the

game, an inclined bottom board, a pair of intermediate oppositely and vertically inclined intercommunicating boards, tortuous runways formed thereon which communicate at different points with the openings 70 in the game board, playing elements which may be manipulated on the game board to pass through said openings on to the runways by which their path of travel is controlled and means operated by an opposing 75 playing element for directing said playing elements to different destinations representing different plays of the game.

4. A game apparatus comprising a game board having a playing surface formed thereon, and having a plurality of openings representing different plays of the game formed therein, an inclined bottom board, a series of pockets formed at one end thereof representing different plays of the game, a pair of intermediate oppositely and vertically inclined intercommunicating boards, tortuous runways formed thereon in communication with said openings, playing elements adapted to be manipulated to pass 80 through said openings onto said runways by which their path of travel may be controlled, and means for directing said elements after leaving said runways into one 85 of the said pockets.

5. A game apparatus comprising a game board having two sets of openings formed therein representing certain plays of the game, a plurality of playing elements which may be manipulated on said playing board 90 to pass through said openings, a bottom board provided with pockets, means disposed below said playing board to direct the elements passing through one of the sets of openings and adapted to direct the elements to a certain destination representing 95 a certain play of the game, a pivotally mounted member normally permitting said element to reach said destination, and means associated with the second set of openings 100 whereby elements passed through said openings will actuate the pivotally mounted member to direct the first named playing 105 element to a destination other than the one named.

6. A game apparatus comprising playing elements, a playing surface having two sets of apertures formed therein representing different plays of the game, means formed beneath the game board representing the 110 three bases of the game, means associated with one of said sets of apertures whereby playing elements passed through the apertures will be normally directed to said bases, means associated with the second set of apertures adapted to direct a playing element 115 passed through the last named apertures toward the path of travel of the element passed through the first set of apertures, and means interposed in said path of travel 120 125 130

adapted to be actuated by elements passed through the second named apertures to divert the playing element passed through the first named apertures to a position representing out of play.

7. A game apparatus comprising a game board having two sets of apertures formed therein representing different plays of the game, said game board having a slightly concaved surface, playing elements adapted to be rolled along said surface and to pass through said apertures, means associated with one of the sets of said apertures whereby playing elements passing therethrough will be normally delivered to a certain point representing the bases, means associated with the second of said sets of apertures whereby playing elements passing therethrough will be delivered to a point in the path of the first named playing element, and means actuated by the second played playing element for interrupting said path and opening a second course which the first played element may pursue.

25 8. In a game apparatus of the character described the combination with the game board and the oppositely and vertically inclined intercommunicating boards disposed below the same, of three openings formed at the front end of the game board, a common runway formed on the intermediate inclined board disposed below the same, a lever pivotally mounted thereon and having an arm disposed crosswise of the runway, a plurality of pockets formed at the rear end of the game board, a movable bottom section for said pockets, and a connection between the lever and the movable bottom section.

9. In a game apparatus of the character described the combination with the game board and the oppositely and vertically inclined boards disposed below the same, of a plurality of openings formed at the rear end of the game board, a tortuous passage formed on the inclined board disposed below the same communicating with said openings, an opening formed in said inclined board at the end of said tortuous passage, and gravity operated means for opening and closing said opening.

10. In a game apparatus of the character described the combination with the game board, oppositely and vertically inclined boards disposed below the same, said game board having a plurality of openings formed at the rear end of a tortuous passage formed on the inclined board disposed below the same communicating with said openings, an opening formed in said inclined board at the end of said tortuous passage, a pivotally mounted member disposed adjacent the other intermediate inclined board, a runway on said member, a runway on the board communicating therewith, and a bridging plate carried by said pivotally mounted member

adapted to open and close the opening at the end of the tortuous passage.

11. In a game apparatus of the character described a game board, a plurality of pockets formed at the rear end thereof, a movable bottom section for said pockets, a plurality of pockets formed at the front end of the game board and below the same, an inclined bottom section communicating with the front and rear pockets, a pair of intermediate oppositely inclined boards disposed between the game board and the bottom section, openings formed in the game board communicating with the respective intermediate boards and the upper ends thereof, runways on said boards communicating with the openings, and runways on the bottom section communicating with the runways on the oppositely inclined intermediate boards and with the front and rear pockets.

12. In a game apparatus of the character described the combination with the game board and two oppositely inclined boards disposed below the same, of a tortuous passage formed on the uppermost of said intermediate boards, a plurality of openings formed in the game board at the rear end thereof communicating with the upper end of the tortuous passage and at different points thereof, a lever disposed on one side of the game board, a runway on said uppermost board terminating above the free end of said lever, an opening in said board at the lower end of the tortuous runway, a second runway formed on the other inclined board communicating with said opening, a stop pin at the end of said runway, and a movable guide plate carried by the lever forming one side of said runway.

13. In a game apparatus of the character described the combination with the game board and two oppositely inclined boards disposed below the same, of a tortuous passage formed on the uppermost of said intermediate boards, a plurality of openings formed in the game board at the rear end thereof communicating with the upper end of the tortuous passage and at different points thereof, a lever disposed on one side of the game board, a runway on said uppermost board terminating above the free end of said lever, an opening in said board at the lower end of the tortuous runway, a second runway formed on the other inclined board communicating with said opening, a stop pin at the end of said runway, a movable guide plate carried by the lever forming one side of said runway, and manually operated means for raising and lowering said plate.

14. In a game apparatus of the character described the combination with the game board and two oppositely inclined boards disposed below the same, of a tortuous passage formed on the uppermost of said intermediate boards, a plurality of openings

formed in the game board at the rear end thereof communicating with the upper end of the tortuous passage and at different points thereof, a lever disposed on one side of the game board, a runway on said uppermost board terminating above the free end of said lever, an opening in said board at the lower end of the tortuous runway, a second runway formed on the other inclined board communicating with said opening, a stop pin at the end of said runway, a movable guide plate carried by the lever forming one side of said runway, manually operated means for raising and lowering said plate, and means cooperating with the second named inclined board for opening and closing the opening at the end of the tortuous passage.

15. A game apparatus comprising a game board provided with openings, oppositely inclined intercommunicating boards beneath the same, an inclined bottom board having a plurality of pockets at one end communicating with the inclined boards, a plurality of playing elements adapted to be manipulated so as to pass through the said openings, traverse the inclined boards and lodge in one of the said pockets, and means comprising an opposing playing element for

deflecting the first mentioned playing element from its normal path of travel.

16. A game apparatus comprising a game board provided with openings, oppositely inclined intercommunicating boards beneath the same, playing elements adapted to pass through certain openings in the game board and traverse one of the inclined boards, a playing element adapted to traverse the other inclined board and operate means for intercepting the first mentioned element, and pockets adapted to receive the elements after leaving the inclined boards.

17. A game apparatus comprising a game board having openings therein, a pair of oppositely inclined overlapping boards beneath the same, a bottom board provided with indicating pockets, one of said inclined boards having an orifice therein, playing elements adapted to be manipulated so as to pass through the openings in the game board and fall through the orifice in the inclined board lodging in one of the said pockets, and means controlled by an opposing playing element for bridging the orifice and changing the path of travel of the first mentioned playing element.

LAWRENCE KLINKER.
